(57) **CLAIM**

What is claimed is the ornamental design for a shotgun forend light, as shown and described.

DESCRIPTION

FIG. 1 is a right, front, and top perspective view of the shotgun forend light.

FIG. 2 is a left, rear, and bottom perspective view of the shotgun forend light of FIG. 1.

FIG. 3 is a right side elevation view of the shotgun forend light of FIG. 1, the left side elevation view being a mirror image thereof.

FIG. 4 is a front elevation view of the shotgun forend light of FIG. 1.

FIG. 5 is a rear elevation view of the shotgun forend light of FIG. 1.

FIG. 6 is a top view of the shotgun forend light of FIG. 1.

FIG. 7 is a bottom view of the shotgun forend light of FIG. 1; and,

FIG. 8 is a right side perspective view of the shotgun forend light of FIG. 1 shown in a use configuration with environment.

The dashed lines depict portions of the shotgun forend light that form no part of the claimed design. The dashed lines in FIG. 8 depict environment of a shotgun that forms no part of the claimed design.

1 Claim, 6 Drawing Sheets
